UNITED STATES PATENT OFFICE

102,537

DESIGN FOR AN X-RAY UNIT

Wilbur S. Werner, South Fort Mitchell, Ky., assignor to The Kelley-Koett Manufacturing Company, Incorporated, Covington, Ky., a corporation of Ohio

Application October 7, 1936, Serial No. 65,193

Term of patent 14 years

To all whom it may concern:

Be it known that I, Wilbur S. Werner, a citizen of the United States, residing at 63 Dixie Highway, South Fort Mitchell, in the county of Kenton and State of Kentucky, have invented a new, original, and ornamental Design for an X-Ray Unit, of which the following is a specification, reference being had to the accompanying drawing, forming part thereof,

Figure 1 is a side elevational view of an X-ray unit showing my new design.

Figure 2 is a rear elevational view of an X-ray unit showing my new design.

I claim:

The ornamental design for an X-ray unit, substantially as shown.

WILBUR S. WERNER,
